CENTER PIECE DIVIDER FOR EGG CASES

Isador Glaser, Bronx, N. Y.

Application March 16, 1953, Serial No. 342,644

1 Claim. (Cl. 229—27)

This invention relates to shipping containers and, more particularly, to cases adapted for the shipment of eggs or the like and made of corrugated or solid fiberboard, box-board, or similar strong, lightweight foldable sheet material.

A principal object of the present invention is to provide a case for shipping eggs which can be delivered to the user in knock-down form and which can be easily and quickly set up by the prospective user.

Another object of the invention is to provide a partition member for bracing the walls of the case in extended condition but which permits ready collapse of the case for shipment in knocked-down form.

A further object of the invention is to provide a shipping case for eggs made of fiber corrugated board stock or the like which can be assembled if desired, without the necessity of using metal fasteners or any other metal reinforcing or securing parts.

It is also proposed to provide a shipping case of this kind with means whereby the case may be readily lifted and handled in transferring it from place to place.

It is further proposed to construct a shipping case for eggs which is simple in construction and which may be manufactured and sold at a reasonable cost.

It is still another object of the present invention to provide a shipping case of the above type which includes four novel bottom closure flaps adapted to divide the bottom of the case into equal halves and which provide support for the aforesaid partition member.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is a top plan view of a blank for a shipping case made in accordance with the present invention.

Fig. 2 is a perspective view of the blank completely assembled but with the top closure flaps raised outwardly.

Fig. 3 is a perspective view of the partition member.

Fig. 4 is a front elevational view thereof.

Fig. 5 is a horizontal sectional view taken on the plane of the line 5—5 of Fig. 2.

Fig. 6 is a horizontal sectional view taken on the plane of the line 6—6 of Fig. 2.

Fig. 7 is a vertical sectional view taken along line 7—7 of Fig. 5.

Fig. 8 is a perspective view showing the case in partly collapsed condition.

Fig. 9 is a vertical sectional view taken along line 9—9 of Fig. 5.

Fig. 10 is a front elevational view of a modified form of partition.

Fig. 11 is a perspective view thereof.

Fig. 12 is a perspective view of another modified form of partition.

Referring to the form of the invention shown in Figs. 1

2

to 9, inclusive, the case or box shown herein is formed of fiberboard, cardboard, laminated material or other appropriate composition material and has two side walls 10 and 11. Along the top edge of wall 10 there is a fold line 12, defining the hinge line of a cover flap 13 attached to the top edge and being one-half as wide as the case or box. Along the top edge of wall 11 there is a fold line 12^a, defining the hinge line of a complementary cover flap 13^a attached to the top edge and also being one-half as wide as the case or box. The two side walls of the case are connected by two end walls 14 and 15. Along the top edge of each end wall there is a flap 16, the flaps 16 cooperating with the flaps 13 and 13^a to close the box top in a well known manner.

Referring to Fig. 1, it will be seen that the side wall 10 is connected to end wall 14 by means of fold lines 14^a, while the other end of side wall 10 is connected to end wall 15 by means of fold line 15^a. The side of end wall 15 remote from fold line 15^a is integrally formed with a flap 15^b which is adapted to be bent so as to lie flush with the end of side wall 11 when the blank is folded to the position of Fig. 2, this flap being secured to side wall 11 by means of staples 11^a.

Along the bottom edge of wall 10 there is a fold line 27, defining the hinge line of a bottom flap 28 attached to the bottom edge and being as wide as the case. This flap is provided with a central, longitudinal fold line 29 for a purpose which will hereinafter become clear. Along the bottom edge of wall 11 there is a fold line 30, defining the hinge line of a second bottom flap 31 attached to the bottom edge and also being as wide as the case. This flap is provided with a central, longitudinal fold line 32. Along the bottom edge of each end wall there is a flap 33 extending one-half the length of the case, substantially as illustrated.

Each flap 33 is divided in half by a central longitudinal opening 34 extending from each end wall to the end of each flap.

After securing the flap 15^b to the end of side wall 11 by means of staples 11^a, and with the end walls 14 and 15 and the side walls 10 and 11 disposed at right angles to each other, the flaps 33 are folded upwardly to provide a floor for the case. The flaps 31 and 28 are each then folded at right angles to themselves along fold lines 32 and 29, respectively, whereupon the outer portions of the thus folded flaps are inserted upwardly through the openings 34, as shown in Fig. 2, completing the bottom closure and at the same time dividing the bottom of the case into longitudinal halves.

The flaps 33 are provided with fold lines 35 for a purpose to be hereinafter referred to.

For use as an egg case or other purpose, there is a transverse partition 17, with reversely turned or folded side portions 18 that extend from the top of the partition as viewed in Figs. 1 and 3 to a point midway its ends. At this point, the partition is provided with a score line 19 whereby the portion 20 of the partition below the score line may be folded upwardly around the score or hinge line to a horizontal position, at right angles to the partition, as shown in Figs. 1 and 3. The bent horizontal portion 20 constitutes a brace for the side walls 10 and 11 thereby preventing the collapse of said walls. The folded side portions 18 of the partition are glued or otherwise secured to the side walls. The partition is centrally located so as to divide the case into two compartments, and to furnish a rigid reinforcement centrally of the case. The flaps 13 and 13^a are adapted to fold inwardly over the top edge of the partition 17.

The end walls 14 and 15 are formed with cutout openings 24 which form hand hold openings for transporting the case from place to place.

In using the case for shipping eggs, each compartment

will contain a stack of conventional fillers and flats (not shown) for holding the individual eggs. The horizontal bracing portion 20 of the partition 17 will rest on one of said devices and be supported thereby. Such devices with the partition 17 and bracing portion 20 will assist in the general bracing of the case from end to end and from side to side.

As shown in Fig. 9, the flaps 33 may then be folded upwardly along fold lines 35 on both sides of flaps 28 and 31, dividing the case longitudinally and providing lateral reinforcement intermediate side walls 10 and 11 and flaps 28 and 31. It will also be noted that the end of the left hand flap 33 when so bent will support the outer end of portion 20 of partition 17, as shown in Fig. 9, providing a shelf-like structure. It will also be noted that upward bending of portion 20 is limited by abutment with the bottom edge of one side portion 18, as shown in Fig. 2. Thus the flaps 33, 28 and 31 also divide the interior of the case into individual compartments which may receive fillers and flats.

It will be understood that the edges of the walls of the case engage the underside of the cover flaps and thus give good support thereto. Additionally, the top edge of the partition 17 gives further support transversely to the center of the top flaps 13 and 13^a.

In order to collapse the the case, the top and bottom flaps 13, 13^a, 16, 28, 31 and 33 are opened outwardly and the horizontal bracing portion 20 of the partition 17 is pressed downwardly into a prolongation of the partition as shown in Fig. 8. The walls of the case are then pressed toward each other and because of the reverse folds 18 of the partition 17, all folds or angles open outwardly and the case may be folded down substantially flat without tending to break or stretch the fiberboard at any corner fold.

The flaps 33 may be folded upwardly to lie flush with the inner sides of end walls 14 and 15 before pressing the side walls together, making a more compact unit. The flaps 28 and 31 may then be folded upwardly against the side walls 10 and 11 providing an extremely compact unit for shipping.

The case is readily and quickly set up by opening the walls of the case and pressing the portion 20 of the partition to horizontal position between the side walls.

In the modified form of partition 17' shown in Figs. 10 and 11, the portion 20' thereof below the score line is formed with folded side portions 25 on both of its side edges. When the portion 20' is folded to horizontal position, the side folds 25 thereof loosely but frictionally engage the side walls 10 and 11 of the case thereby affording additional rigidity to the case.

In all other respects, the form of partition shown in Figs. 10 and 11 is similar to the form of partition shown in Figs. 2 to 9 and similar reference numerals are used to indicate similar parts.

Fig. 12 illustrates a further modified form of partition 17" similar in construction to the form of partition of Figs. 2 to 9, but provided with a finger opening 26 in the bendable lower portion 20" to facilitate manipulation of the lower portion.

It will be seen that I have provided a strong, serviceable egg case or carton, with a cover and bottom that can be turned back, which case can be easily set up or folded.

While I have illustrated and described preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

A shipping case for eggs and the like having side and end walls and a bottom closure, a vertically disposed Z-shaped partition between the side walls and hingedly connected thereto, an integral horizontally disposed bracing member for the side walls hingedly connected to the partition, said bottom closure comprising end flaps integrally connected to the bottom edges of said end walls and foldable upward, each of said end flaps extending substantially one half the length of the case and having a central, longitudinal opening dividing said flaps into two substantially equal halves, and side flaps integrally connected to the bottom edges of said side walls and foldable upward, each of said side flaps extending substantially the width of the case and having a central longitudinal fold line whereby the outer portions of said side flaps may be folded upwardly into the case through said openings in said end flaps and brought into juxtaposition with each other, said end flaps having transverse fold lines permitting the same to be folded upwardly on each side of said juxtaposed outer portions of said side flaps whereby to reinforce said case intermediate said side walls and said juxtaposed outer portions of said side flaps and to divide the bottom of the case into partitions, one of said end flaps at the end thereof abutting the end of said bracing member when said flap is folded upwardly along said transverse fold lines.
